PHONOGRAPH REPRODUCER

Filed Jan. 23, 1926

UNITED STATES PATENT OFFICE

ADOLPH A. THOMAS, OF NEW YORK, N. Y.

PHONOGRAPH REPRODUCER

Application filed January 23, 1926. Serial No. 83,190.

This invention relates to the art of reproducing recorded sound, and its object is to provide a new and improved reproducer for phonographs or similar acoustic machines 5 utilizing sound records for loud reproduction.

The basic idea of my invention comprises a combined electro-mechanical reproducer as a single unit capable of reproducing from 10 a record either mechanically through a diaphragm or electrically through suitable electromagnetic mechanism. There is one needle arm for actuating the diaphragm and a second needle arm for operating the electric 15 reproducing mechanism. Either needle arm is readily brought into playing position, as more fully explained later on.

The acoustic reproduction of phonograph records has heretofore been carried out in 20 two ways: first, mechanically by means of a diaphragm actuated by the record needle, the diaphragm vibrations being amplified through the tone arm and horn of the machine; second, electrically by causing the 25 needle to operate a microphone or an electro-magnetic device mounted on the tone arm for producing variable currents in a telephone receiver, which may be located in the phonograph cabinet or at a distance there- 30 from. In this electric reproduction, the tone arm is not utilized as an amplifier of sound waves, but the telephone receiver is acoustically connected with an amplifying horn or operates through a loudspeaking diaphragm.

35 In phonographs utilizing mechanical reproduction, the maximum volume obtainable is necessarily limited by the maximum vibrations of the needle-actuated diaphragm as amplified through the tone arm and the horn. 40 The volume of sound thus produced is usually sufficient for an ordinary room in a house or an apartment. But there are times when it is desirable to obtain a greater volume of reproduction from a record than is possible 45 with a mechanical sound box—as, for instance, where a phonograph is played in a large hall or in the open. To meet this condition, it has been proposed to use an electric reproducer in which the needle operates a 50 microphone or otherwise causes variable cur-

rents to flow in a telephone receiver. These currents may be amplified or stepped up to increase the volume of reproduction to the required degree. It is recognized that each method of phonographic sound reproduction 55—that is, the mechanical and the electrical—has its advantages: the mechanical method requires no batteries, circuits, etc., and the electrical method permits greater acoustic amplification, together with a finer regulation of volume.

In order to combine the advantages of mechanical and electrical sound reproduction in a single machine, I have provided a combined mechanical and electrical reproducer 65 in a single unit pivotally mounted on the tone arm. This double-acting unit has two needle arms so arranged that the needle holders project from the periphery of the reproducer casing at radially separated points, which 70 may be 180° or 90° apart, or at any other convenient angle. One of the needle arms actuates a diaphragm which sends the sound vibrations through a tone arm in the usual way. The other needle arm operates a suitable electric reproducer which is connected to or controls a loudspeaker. The casing that carries the parts is rotatably mounted on the tone arm or on the so-called goose-neck swivelled thereon. Releasable locking means on 75 the tone arm and casing automatically lock the casing in correct position for either needle arm, and yet readily permit adjustment of the casing into either of its playing positions. Thus, by a slight turn of the casing, 80 you can reproduce mechanically or electrically, as you will, from a phonograph record.

The basic idea of my invention may be embodied in various constructions, of which an illustrative example is shown in the accompanying drawings, where

Fig. 1 shows a side view of a combined mechanical and electrical phonograph reproducer constructed in accordance with my invention, the cover of the casing being removed 95 to show the inside;

Fig. 2 is a cross-section approximately on the broken line 2—2 of Fig. 1;

Fig. 3 is a transverse view in section on line 3—3 of Fig. 1;

Fig. 4 is a fragmentary detail view on line 4-4 of Fig. 2; and

Fig. 5 shows a rear view of the reproducer casing along the broken section line 5-5 of Fig. 2.

Before proceeding with a detailed description of the drawings, I want to make it plain that the various views are shown on an enlarged scale for clearness. For the same reason, the different parts in their assembled form are not to be taken as correctly proportioned, but are purposely shown exaggerated in their dimensions.

The various parts that go to make up this double-acting reproducer are carried by a casing C of suitable construction and design. In the present instance, the casing consists of a back-plate 1, a cylindrical body section 2 and a front plate or cover 3. These three parts are separably secured together in any practical way, as by screws 4 engaging in bosses 5 and 6. The bosses 5 are on the inside of the casing to engage the screws that hold the cover 3 in place, but the rear bosses 6 are for convenience arranged outside the casing, as best shown in Fig. 5. The casing C may be formed out of light non-magnetic metal, such as aluminum or an aluminum alloy, but it can be made of a non-metallic composition having the required hardness and strength.

The cylindrical body 2 of casing C is provided with an annular flange 7 which forms a shallow chamber or recess 8 for mounting a vibratory diaphragm 9 of proper design. The particular manner of supporting the diaphragm is immaterial. In the drawings I have shown the diaphragm held clamped between a pair of rings or washers 10 of sound-deadening material, such as rubber, felt, leather and the like. When the back-plate 1 is taken off, the diaphragm is accessible for inspection or removal. The center of diaphragm 9 is connected to the inner end of a needle arm 11 pivoted to the body section 2 of the casing in any practical way, as by means of bearing screws 12 mounted in a pair of lugs 13 projecting from the periphery of the casing. The outer end of needle arm 11 is in the form of a needle holder 14 adapted to hold phonograph needles in record-playing position. The needle arm 11 projects into the casing through a slot 15. The annular flange 7 is slotted at that point so as not to interfere with the movements of the needle arm.

Within casing C is mounted a circular magnet 16, preferably of the permanent type. It is convenient to secure the magnet to the circular flange 7, as by means of screws 8'. Magnet 16 terminates in poles 17, which project forwardly and carry pole pieces 18, usually made of soft iron or soft steel. In the airgap between the axially aligned pole pieces 18 operates a coil 19 secured to the inner end of a second needle arm 20, which is pivoted to

the casing in any practical way. In the present embodiment, I have shown the outer portion of the needle arm 20 secured to a flat spring-blade 21 mounted at its ends in a pair of lugs 22 projecting from the casing. The spring-blade 21 allows the needle arm 20 to vibrate transversely of the casing, and yet it firmly supports the needle arm against any longitudinal thrust. The spring 21, therefore, acts like a pivot and automatically restores the needle arm to normal position, so that no separate restoring and centering spring is necessary. This particular feature forms the subject matter of a copending application of mine and is not herein claimed. In a broader aspect of my invention the needle arm 20, like the other needle arm 11, may be pivotally mounted on the casing by any suitable means. When I refer to the parts 11 and 20 as needle arms, I mean broadly any practical stylus-carrying members, irrespective of the particular form of stylus used.

The coil 19, which in practice is quite small and very light, may be secured to the free end of needle arm 20 by means of a band 23, the ends of which overlap the free end of the needle arm, so that the parts may be rigidly secured together by means of a single pin or screw 24. The outer end of needle arm 20 is provided with a needle holder 25, which may be like the needle holder 14, or of any other practical construction. A slot 26 in the periphery of body section 2 allows the needle holder 20 to project into the casing. If necessary, the cover 3 of the casing may be formed with a bulge 27 to provide sufficient room for the vibrations of needle arm 20.

The resilient spring support 21 normally holds the needle arm 20 in such position that the coil 19 is in axial alignment with the pole pieces 18, so that normally the maximum flux passes through the coil. It is preferable to make the pole pieces 18 of cylindrical form and of approximately the same diameter as the internal diameter of the coil. In this construction, as the coil vibrates transversely of the pole pieces, the magnetic flux through the coil varies correspondingly, so that current impulses are generated in the circuit of the coil. The greater the amplitude of vibration of coil 19, the greater are the flux variations. Consequently, the current impulses generated in coil 19 are an electrical representation (as it were) of the mechanical vibrations of needle arm 20. As seen in Fig. 2, the needle vibrations are transmitted to the coil 19 in considerably amplified ratio.

Therefore, the smallest needle vibrations are sufficient to cause current impulses to be generated in coil 19.

It goes without saying that coil 19 is properly connected in circuit to utilize the current impulses therein for the reproduction of the recorded sound. These current impulses may be amplified electrically before they are

used to operate or control a loudspeaker or other acoustic mechanism. As these circuit connections are well understood by electrical engineers, I need not show or describe them in detail. It is sufficient that I show a pair of leads 28 connected to the ends of coil 19. These conductors pass through a small hole in the casing to a pair of terminals or binding posts 29 mounted on a small insulating disk 30, which is secured to the back-plate 1 of the casing by screws 31 or otherwise. Since the coil is made of very fine wire, the conductors 28 within the casing do not interfere with the proper vibrations of needle arm 20 and coil 19. To the binding posts 29 are connected wires 32, which lead through a hole 33 in the cylindrical hub 34 of the casing, as best shown in Fig. 5. The binding posts 29 may have wing-nuts for the ready connection and disconnection of the wires 32 without tools, as when it is desired to remove the sound box from the tone arm.

The reproducer casing is mounted in correct radial position on a tone arm 35, of which the outer portion is shown in Fig. 2. The hub 34 of casing C fits snugly and yet rotatably on the free end 36 of the tone arm. A suitable stop, such as an annular rib 37, limits the inward movement of the hub 34 when the reproducer is inserted on the tone arm.

In order to insure the correct angular position of the reproducer on the tone arm with respect to each needle arm, suitable locking means is provided for firmly but releasably locking the casing in either of its playing positions. Such locking means may be embodied in various forms, one of which is shown in Figs. 2 and 4 by way of example. The outer end of tone arm 35 is provided with a spring-finger 38 carrying at or near its free end a lug 39 of rounded shape. The hub 34 of the reproducer casing is provided with a pair of recesses 40 for receiving the lug 39, which fits snugly and firmly in either recess for holding the reproducer casing locked in position. The engagement between the lug and either recess is such that a slight turning force exerted on the casing is sufficient to force the lug out of the recess, so as to permit adjustment of the reproducer into the other playing position. The angular arrangement of the locking lug 39 and the two recesses 40 is such that, when the lug rests in one recess, the reproducer 11 is in playing position; and when the lug engages in the other recess, the needle arm 20 is in playing position. It is, therefore, a very simple matter to adjust the reproducer for either mechanical or electrical reproduction. It is not necessary to take the reproducer off the tone arm to effect this adjustment, nor is it even required to use any tools. A slight twisting force with the fingers is sufficient to turn the casing from one position to the other. The lug 39 automatically locks the

casing in proper position without any attention on the part of the operator.

In the example shown in the drawings, the two needle arms 11 and 20 are shown at an angle of 180°, and consequently, the recesses 40 are spaced at the same angle. It will be clear, however, that any other angular spacing of the needle arms may be used. For instance the two needle arms could be arranged at an angle of 90°, so that only one-quarter of a turn would be necessary to adjust the casing into position for either mechanical or electrical reproduction.

In the broader aspect of my invention, the needle arm 20 may operate any suitable electric reproducing mechanism. The coil 19 and the associated magnet represent only one of various electromagnetic reproducing devices that may be housed within the casing, and I therefore do not limit myself to any particular construction of electric reproducing mechanism controlled or operated by the needle arm 20.

If it is for any reason necessary or desirable to remove the reproducer from the tone arm, the wires 32 are first disconnected from the binding posts 29. This is easily done by loosening the wing-nuts of the binding posts. Then the casing is given a slight twist to force the locking lug 39 out of its recess, whereupon the casing may be slipped off the tone arm. Concealment of the wires 32 within the tone arm adds to the neatness of the phonograph as a whole.

Although I have herein shown and described a certain specific construction, I want it understood that I have done so in order to explain my invention fully and clearly to those skilled in the art, and not by way of restriction or limitation. The basic idea of my invention may be mechanically embodied in various other ways without departing from the scope of the invention as defined in the following claims. It is apparent that my reproducer may be so mounted on the supporting arm as to play either lateral-cut records or vertical-cut records. My new double-acting reproducer constitutes a unitary device sold separately as a new article of manufacture for attachment to a phonograph tone arm, or it may be sold with the tone arm to which it is attached.

What I claim as my invention is:

1. As a new article of manufacture for attachment to phonographs, a casing carrying a complete mechanical and a complete electrical reproducing mechanism, each of said mechanisms including a stylus arm pivoted on said casing, which is adapted to be mounted on a tone arm and adjustable to bring either mechanism into playing position.

2. As a new article of manufacture for attachment to phonographs, a casing containing a complete mechanical and a complete

electrical reproducing mechanism, each of said mechanisms including a stylus arm pivoted on the casing, and said casing being adapted to be mounted on a tone arm and revolved thereon as an axis to bring either mechanism into playing position.

3. As a new article of manufacture for attachment to phonographs, a casing carrying a pair of independently pivoted stylus arms, 10 mechanical reproducing means carried by said casing and operated by one of said arms, and electrical reproducing means also carried by said casing and operated by the other stylus arm, said casing being adapted to be 15 mounted on a tone arm so as to bring either stylus arm into playing position.

4. As a new article of manufacture for attachment to phonographs, a combined mechanical and electrical reproducer comprising 20 a support, a diaphragm and electric reproducing means mounted on said support, a stylus arm pivoted on said support for actuating said diaphragm, and a second stylus arm pivoted on said support for operating 25 said reproducer means, said support and all parts carried thereby being adapted to be mounted on a tone arm so that either stylus arm can be moved into playing position.

5. As a new article of manufacture for attachment to phonographs, a combined mechanical and electrical reproducer comprising 30 a casing, a diaphragm and electric reproducing mechanism mounted in said casing, a pair of stylus arms pivoted on said casing for operating 35 said diaphragm and said reproducing mechanism respectively, said casing being adapted to be mounted on a tone arm and rotatable thereon to bring either stylus arm into playing position.

40 6. As a new article of manufacture for attachment to phonographs, a substantially cylindrical casing provided with two stylus arms arranged to project from the periphery of said casing at radially separated points, a 45 diaphragm mounted on said casing and connected to one of said stylus arms, and electrical reproducing mechanism in said casing operated by the other stylus arm, said casing being adapted to be rotatably mounted on a 50 tone arm to bring either stylus arm into playing position.

7. As a new article of manufacture for attachment to phonographs, a casing carrying 55 a diaphragm for mechanical reproduction and electromagnetic mechanism for electrical reproduction, and a pair of separately movable members mounted on said casing for selectively operating said diaphragm and said mechanism independently of each other, 60 said casing being adapted to be mounted on an arm to bring either of said reproducing devices into playing position.

8. In a combined mechanical and electrical phonograph reproducer, a cylindrical casing 65 provided with an integral interior flange

arranged between the opposite ends of the casing to divide the same transversely into two chambers, a diaphragm mounted in one of said chambers, and electric reproducing mechanism in the other chamber.

9. In a combined mechanical and electrical phonograph reproducer, a cylindrical casing provided with an integral flange arranged between the opposite ends of the casing to divide the same transversely into two 70 chambers, a diaphragm mounted in one of said chambers, and electric reproducing mechanism in the other chamber, said mechanism including a magnet secured to said flange.
